(57) **CLAIM**

The ornamental design for a container carrier, as shown and described.

DESCRIPTION

FIG. 1 is a perspective view of a container carrier, showing our new design in a folded configuration and in a condition of use with three containers;

FIG. 2 is a perspective view thereof, illustrated in a flat configuration;

FIG. 3 is a top plan view of FIG. 2, the bottom plan view being a mirror image thereof;

FIG. 4 is a left-side elevational view of FIG. 2, the right-side elevational view being a mirror image thereof;

FIG. 5 is a front elevational view of FIG. 2; and,

FIG. 6 is a rear elevational view of FIG. 2.

The broken lines showing bottles in FIG. 1 depict environmental structure. The dot-dash broken lines in the figures depict a boundary of the claimed design. The remaining broken lines represent portions of the container carrier. The broken lines form no part of the claim.
